DISPLAY STAND

Alan K. Snyder, River Forest, Ill., assignor to Chicago
Display Company, Melrose Park, Ill.

Filed July 28, 1972, Ser. No. 276,077

Term of patent 14 years

Int. Cl. D20—02

U.S. Cl. D6—24

FIG. 1

FIG. 2

FIG. 3

FIG. 4

FIG. 5

FIG. 1 is a perspective view of a display stand showing my new design;

FIG. 2 is a cross-sectional view taken along line 2-2 of FIG. 1, showing the bottom portion of the display stand;

FIG. 3 is a side elevation view of the display stand shown in FIG. 1;

FIG. 4 is a cross-sectional view taken along line 4-4 of FIG. 3; and

FIG. 5 is a cross-sectional view taken along line 5-5 of FIG. 3.

I claim:

The design for a display stand, substantially as shown.
